UNITED STATES PATENT OFFICE.

JOHN OPACITY, OF NEWARK, NEW JERSEY.

CROSS-STITCH ATTACHMENT FOR PATCH MACHINES.

Application filed September 29, 1924. Serial No. 740,422.

To all whom it may concern:

Be it known that I, JOHN OPACITY, a citizen of Czechoslovakia, residing at Newark, in the county of Essex and State of New Jersey, have invented certain new and useful Improvements in Cross-Stitch Attachments for Patch Machines, of which the following is a specification.

This invention relates to improvements in sewing machines and particularly to the presser-foot of such machines as are used for sewing leather and like goods.

The principal object of the invention is to provide means for raising the presser-foot 15 between each stitch, permitting the goods to be moved laterally as well as advanced in the direction of the feed, producing angularly disposed cross stitches whereby two pieces of goods may be secured at their 20 edges without overlapping the joint.

A further feature of the invention resides in supplying means for retaining the presser-foot in a raised position an unusually long period of time, during which the goods may 25 be adjusted in readiness to receive the next stitch.

Another aim is in the provision of an attachment to be applied to sewing machines as presently constructed, without change 30 of and kind whatever, whereby the presser-foot action is retarded, in conformity with the results to be obtained.

These several objects are accomplished by the novel construction and arrangement of 35 parts hereinafter described, and shown in the accompanying drawing, forming a material part of this disclosure, and in which:—

Figure 1 is a rear side elevational view of a conventional type of leather sewing 40 machine to which an embodiment of the invention is attached.

Figure 2 is a front elevational view of the sewing machine head, the presser-foot being shown in its lowermost position.

Figure 3 is a similar view of the same but showing the needle bar and presser-foot in a raised position.

Figure 4 is an enlarged front view of the attachment in detail.

Figure 5 is a fragmentary plan view of a piece of material having a single row of straight stitches as are usually performed by the machine.

Figure 6 is a similar view showing two pieces of material arranged edge to edge and sewn with a zig-zag row of stitches such

as may be produced by means of the attachment.

In the drawing, the frame of the machine is shown to consist of a base 10, from which 60 extends a narrow platform 11 carrying a work plate 12.

A standard 13 supports an overhanging arm 14 having a head 15 and in which is rotatably mounted a shaft 16 carrying a 65 hand wheel 17, drive pulley 18 and cam 19, the latter operating a lever 20 pivoted substantially central of the arm 14 on the pin 21.

The forward end of the lever 20 carries 70 a spring actuated take-up 22, below which is connection 23 pivotally engaging the upper extremity of the needle-bar 24, causing it to operate reciprocatively in the head.

A needle 25 is fixed in the lower end of 75 the needle-bar, the needle passing through the work or throat-plate 12 to engage the thread carried on a bobbin, not shown, in the arm 11, said needle also passing through the presser-foot 26, the latter element being 80 attached to the lower end of the presser-foot bar 27.

The element 27 is moved by cam mechanism, as indicated at 28 in the machine head and driven by the shaft 16 in the ordinary 85 manner; it may be raised manually by the lever 29, pivoted at 30 on the head, so as to raise and lower the presser-foot as desired, the presser-foot, when thus raised, being freed from the cam 28. 90

Thread tensioning and guide means 32 are arranged on the head of the machine and it is to be understood that the machine is fully complete in all its parts and function, and will produce work of the kind indicated in 95 Figure 5, or in other words plain seams.

The action of the cam 28 is very brief, merely sufficing to raise the presser-foot off the work during the feeding of the work and allows no time for moving the goods 100 sideways as is required to produce the stitches shown in Figure 6.

To accomplish this, the ordinary pin connection between the lever element 23 and needle-bar 24, is removed and for it is substituted a bent rod 35, its angular down-turned end being connected by a pivot 36 to a clevis 37 at one end of a stem 38 adjustably engaged in a turnbuckle nut 39, provided with right and left hand threads, 110 one of which is suited to the stem 38 and the other to a similar stem 40.

The stem 40 has a flattened head 41 through which passes a pin 42, connecting a loop 43 adapted to operatively engage the presser-foot bar lever 29.

It will now be seen that the lever 29 will depend for operation on the lever 20 rather than on the cam 28, and thus is given a greater lift or rise and further, is held in a raised position a greater duration of time, during which the work parts may be shifted laterally by hand to produce the row of stitches shown in Figure 6.

It is found in practice that an operator is easily able to produce excellent and uniform stitching of the kind shown, and it will be obvious that plain stitching, if de-

sired, may be effected by removing the pin 36 and disconnect the loop 43.

Having thus described my invention, what I claim as new and desire to secure by Letters Patent, is:—

In a sewing machine having a reciprocating needle-bar and a presser-foot bar, said presser-foot bar being provided with a manually operating raising lever, a loop engageable with said lever, a rod actuated by the needle-bar, and right and left hand screw-threaded connections between said loop and rod.

In witness whereof I have affixed my signature.

JOHN OPACITY.
